UNITED STATES PATENT OFFICE.

JOHN RICHARDSON BAILEY, OF BALTIMORE, MARYLAND, ASSIGNOR TO
MAURICE LAUPHEIMER, OF BALTIMORE, MARYLAND.

STEAM-BOILER FURNACE.

SPECIFICATION forming part of Letters Patent No. 707,496, dated August 19, 1902.

Application filed April 7, 1902. Serial No. 101,817. (No model.)

To all whom it may concern:

Be it known that I, JOHN RICHARDSON BAILEY, a citizen of the United States, residing at Baltimore, in the State of Maryland, 5 have invented certain new and useful Improvements in Steam-Boiler Furnaces, (Case B;) and I do hereby declare the following to be a full, clear, and exact description of the invention, such as will enable others skilled 10 in the art to which it appertains to make and use the same.

My invention relates to improvements in furnaces for steam-boilers; and it is intended to provide a furnace in which the carbon of 15 the coal will be entirely consumed into carbon dioxide, thus not only securing higher efficiency for the furnace, but also insuring such complete combustion that the furnace will be practically, if not entirely, smokeless.

20 A great deal of the smoke passing from furnaces is occasioned by the impact of the heated gases on the cool shell of the boiler before complete combustion of the fuel has been secured, thus causing a chilling of said gases 25 and the deposit of carbon in the solid form, which carbon not being afterward ignited is carried up the smoke-stack in the form of smoke. This is not only wasteful of the fuel, but is especially objectionable in cities, where 30 the smoke nuisance is a crying evil. I accomplish these ends by the structure that will be hereinafter described.

Reference is had to the accompanying drawings, in which the same parts are indicated 35 by the same letters throughout both views.

Figure 1 represents a section through the furnace along the line 1 1 of Fig. 2. Fig. 2 represents a double section, the left half being along the line 2 2 of Fig. 1 and the right 40 half being along the line 2^a 2^a of Fig. 1. In this figure the boiler is shown not in section, but in end elevation.

I have shown a horizontal tubular boiler as used in connection with the furnace, the said 45 boiler being of the common well-known type; but any other form of boiler may be used, if desired.

Referring now to the drawings by letter, A represents the ash-pit, and B the grate, which 50 may be of any ordinary or suitable type.

C represents the fire-box.

The ash-pit and fire-box have doors of any suitable construction a and c.

D represents the front bridge-wall, behind which the combustion-chamber E is situated. 55 This combustion-chamber has a floor, which is composed of two parts F and F', sloping toward each other and forming a step-down or shoulder f to arrest the flow of the gases. The point f is underneath the deflector G, 60 which is in the form of an arch, with the front face indented, as at g, to further arrest the gases. This arch extends between the side walls, and the deflector spans the space between the said walls in the furnace below 65 the crown h of the arch H. This arch H touches the bottom of the boiler at its apex, and the space between the boiler and the arch is walled up in front, as shown at K, to permit the passage of part of the products of 70 combustion above the arch H.

L is the rear bridge-wall, and M is the back connection.

N is the boiler, shown as a cylindrical fire tubular boiler; but, as before stated, this may 75 be of any desired type.

P is the front connection, terminating in the uptake Q.

R is a pipe perforated on its rear face to deliver steam or air into the furnace. Suitable 80 connections for said pipe to the boiler itself for steam and to any source of air-supply (not shown) would of course be provided. The steam is admitted when desired for the purpose of blowing the ashes out of the hearth 85 or for creating a forced draft, if desired, and air may be admitted when the steam is not on for the purpose of promoting the combustion in the combustion-chamber E; but this pipe may be omitted, if desired. This pipe R 90 is preferably partly inclosed in a recess in the rear face of the bridge-wall D, as shown in Fig. 1, to protect the metal of the pipe from the high heat of the furnace.

The products of combustion passing from 95 the grate do not come directly in contact with the bottom of the boiler, being protected therefrom by an intermediate layer of more or less dead air, but pass into the combustion-chamber E in the direction of the arrows. 100 In this combustion-chamber the direction of highly-heated gases is deflected downward by

the deflector G, and their motion is arrested somewhat, while at the same time the highly-heated brick walls surrounding this combustion-chamber E prevent any chilling of the 5 products of combustion, and the result is complete combustion of the carbon and a volume of smokeless and highly-heated gases which enter into the back connection M. The combustion being complete, little or no 10 liberation of carbon occurs when the highly-heated gases enter the fire-tubes of the boiler, and as a consequence the gases escaping from the front connection P and uptake Q are practically colorless.

15 In the construction of the flat arch G, I preferably use fire-bricks of a large size and specially made for the purpose.

It will be obvious that various modifications might be made in the herein-described 20 device which could be used without departing from the spirit of my invention.

Having thus described my invention, what I claim, and desire to secure by Letters Patent of the United States, is—

25 1. In a steam-boiler furnace, the combination of a fuel-chamber, front and rear bridge-walls, a combustion-chamber between said walls provided with an inclined floor, an arch extending over said walls, a boiler located 30 above said arch and contacting with its highest point, and a baffle-plate extending downwardly from about the center of said arch, said baffle-plate being provided with recesses or pockets on its front projecting surface, 35 substantially as described.

2. In a boiler-furnace, the combination of a casing provided with a fuel-chamber near one end, front and rear bridge-walls, an arch extending completely over said bridge-walls 40 and supported by the sides of the casing, a boiler extending over said fuel-chamber and touching said arch at its highest point, a wall or partition extending upwardly from the front of said arch and around the lower part 45 of said boiler, and a baffle-plate extending downwardly from substantially the center of said arch and provided with recesses or hollows on its front face, substantially as described.

3. In a boiler-furnace, the combination of 50 a casing, a fuel-chamber near one end thereof, front and rear bridge-walls, a double inclined floor extending between said bridge-walls, one part of said floor being higher than the other so as to form a retarding-corner, an arch 55 sprung from the side walls of said casing and extending over said bridge-walls, a boiler mounted in said casing and extending over said fuel-chamber and said arch and touching the highest point of said arch, a partition 60 extending upwardly from the front of said arch and inclosing the lower part of said boiler, and a baffle-plate located near the center of said arch and extending downwardly, said baffle-plate being provided with hollows 65 or recesses on its forward face and being located above the corner in the floor between said bridge-walls, substantially as described.

4. In a boiler-furnace, the combination of 70 a casing, a fuel-chamber near one end thereof, front and rear bridge-walls, a double inclined floor, extending between said bridge-walls, one part of said floor being higher than the other so as to form a retarding-corner, an arch 75 sprung from the side walls of said casing and extending over said bridge-walls, a boiler mounted in said casing and extending over said fuel-chamber and said arch and touching the highest point of said arch, a partition 80 extending upwardly from the front of said arch and inclosing the lower part of said boiler, a baffle-plate located near the center of said arch and extending downwardly, said baffle-plate being provided with hollows or recesses on its forward face and being located 85 above the corner in the floor between said bridge-walls, and a perforated air-pipe located behind the front bridge-wall and adapted to supply air to the products of combustion after they have left the fuel-chamber, substantially 90 as described.

In testimony whereof I affix my signature in presence of two witnesses.

JOHN RICHARDSON BAILEY.
